CLOSURE UNIT FOR CHAMBER WALL
OPENINGS

Frank X. Gilg, Chatham, and John C. Singleton,
Jr., Watchung, N. J., assignors to The Babcock
& Wilcox Company, Rockleigh, N. J., a corpo-
ration of New Jersey

Application July 17, 1946, Serial No. 684,374

4 Claims. (Cl. 220—33)

1

The invention herein disclosed relates to the construction and operation of closure units especially adapted for association with chamber wall openings such as are normally provided in the walls of furnaces and other similar closed chambered structures. More specifically, our invention is directed to a type of lance door unit having a pivoted door or cover component slideable with respect to an associated chamber wall opening through which a lance or other implement may be inserted for cleaning heat transfer surfaces interiorly of the chamber.

An object of our invention is the provision of closure means adapted for association with wall openings arranged at relatively close spacings, with a separate unit for each such opening and each operable without interference with adjacently positioned units.

An additional object is the provision of a sliding type door or cover having its opening and closing movement limited to enable the door when closed to completely cover the opening and when open to be guided by its seat into closed position.

A further object is the provision of a closure means having its door or cover member operated by a separate element which also serves to maintain the door tight against its seat when in the closed position.

Our invention also includes as an object the provision of a closure means having an associated frame structure mounted on wall tubes and serving to protect such tubes from injury when inserting a lance or other implement therebetween.

The various features of novelty which characterize our invention are pointed out with particularity in the claims annexed to and forming a part of this specification. For a better understanding of the invention, its operating advantages and specific objects attained by its use, reference should be had to the accompanying drawings and descriptive matter in which we have illustrated and described a preferred embodiment of our invention.

Of the drawings:

Fig. 1 is a fragmentary side elevation illustrating our invention as embodied at various locations in the setting of a water tube boiler unit;

Fig. 2 is an enlarged fragmentary plan section taken along line 2—2 of Fig. 1;

Fig. 3 is a front view of one of the door assemblies included in Fig. 2, indicating also its relation to an adjacent unit;

2

Fig. 4 is a side view of the assembly illustrated in Fig. 3, taken along line 4—4;

Fig. 5 is a sectional view of the assembly, taken along line 5—5 of Fig. 3;

Fig. 6 is a front view, similar to Fig. 3, showing a modification;

Fig. 7 is a side view of the modification, taken along line 7—7 of Fig. 6; and,

Fig. 8 is a sectional view of the modification, taken along line 8—8 of Fig. 6.

The fragmentary views Figs. 1 and 2 illustrate, by way of example, the application of our invention to a known form of boiler unit having horizontally disposed lengths of boiler tubes 10 arranged in a bank over a furnace chamber 12 having a front upright defining wall 13, the tubes 10 being arranged in vertically spaced rows as shown and being also arranged in horizontally spaced rows across the width of the boiler as is customary. The tubes 10 are connected at their upper ends to a transverse boiler drum 14 to which the upper ends of horizontally spaced upright front furnace wall tubes 15 are also connected, other horizontally spaced wall tubes as indicated by centerlines 16 being positioned in a side wall of the boiler. In the arrangement shown, closure units 17 are arranged in a row opposite the spaces 18 between successive wall tubes 15 to permit the insertion of a steam lance, for example, for cleaning the walls of boiler tubes 10 at opposite sides of each intervening vertical lane. Similar closure units may be installed between side wall tubes 16, at locations 19 distributed as indicated in Fig. 1 for example, for cleaning the walls of tubes 10 adjoining each horizontal lane.

Each closure or lance port unit 17 comprises an outer door assembly in which a cover or door 23 is pivoted to an outer frame member 21, together with an inner frame member or sleeve 24 having laterally extending mounting flanges or lugs 25 for securing the unit to wall 13. The mounting lugs 25 preferably terminate at approximately the centerlines of adjacent wall tubes 15 where adjoining lugs are clamped to the tubes by nuts 26 threaded on studs 27 suitably secured to the tubes.

The frame members 21 and 24 are separably connected by cap screws 28 and together provide a continuous lance port or passage 29 therethrough in register with the intertube space 18, the passage 29 having an initial diameter of 2 in., for example, at its outer circular end 31 in frame member 21 and flaring to a somewhat larger diameter at the joint 32 between the mem-

bers, the passage 29 gradually changing to an elliptical cross-section elongated parallel to wall tubes 15 to a dimension of 7 in., for example, at the inner end 34 of sleeve member 24. When studs 35 are provided on tubes 15 such studs are omitted from the wall tube area opposite the inner end 34 of passage 29. The companionate bolting flanges 36 and 37 on the outer and inner frame member respectively are preferably separated sufficiently to receive the sheet metal wall casing 38.

Referring to Figs. 3, 4 and 5, the outer door frame member 21 is provided with a bolting flange 36 of rectangular formation, with holes 39 at the corners for cap screws 28, the diagonals of flange 36 extending at right angles to each other with one diagonal being positioned vertically and thus parallel to wall tubes 15 when assembled as illustrated in Figs. 1 and 2. The frame member or base plate 21 is preferably formed with a raised rim surrounding the circular outer end 31 of lance port 29 and providing a planar annular door seat 41. The door or cover 23 includes a cup-like body portion 42 of generally circular formation and presenting a planar annular seating surface 43 adapted to seat against the companionate base plate surface 41. A thin sheet metal disc 44 is fitted within the recessed portion of cover 23, in edge contact only and providing a relatively dead air space 45, to insulate the main body portion 42 from furnace heat.

The door 23 includes an integral arm portion 46 extending radially from the circular body portion 42, while a bolt 47 extending through arm 46 and secured to a laterally extending lug 48 on base plate 21, suitably by nuts 49 as shown, provides a pivot support for the door permitting door movement about pivotal axis 51 extending normal to the plane of annular door seat 41.

The door 23 is opened and closed by means of an operating lever or bar 53 having a pin-and-socket connection therewith, the member 53 being pivotally supported on bolt 47 and thus movable about a common axis 51 with the door, and having a circular recess or socket 54 therein, slightly conical in cross section, for engagement with a circular and centrally disposed boss or pin 56 on the body portion 42 of the door. An upstanding lug or bracket 57 integral with base plate 21 is formed with a notch 58 in one side thereof for receiving the free latch end 59 of lever 53 when the door is moved into its closed position, in which position the upper inclined surface 62 of the lever is wedged against the correspondingly inclined keeper surface 63 of notch 58 whereby a force is exerted by the lever against boss 56 to clamp door 23 firmly against its seat 41. Surfaces 62 and 63 are suitably inclined at an angle of about 10° to the plane of door seat surface 41.

As indicated in Fig. 5, clearances are provided between adjacent portions of the operating member 53 and door 23 so that the clamping force is applied axially to the rounded tip 64 of boss 56 and thus to only a restricted centrally disposed area of the door, thereby assuring substantially uniform contact throughout the entire door seat area, the height of the boss exceeding the depth of recess 54 and furthermore the tip of the boss being engaged by a substantially flat surface 65 which forms the base of the recess. The degree of clamping force applied to the cover may be adjusted to suit operating conditions depending, for example, on the force applied to the

lever or bar 53 to rotate it into latching position, the lever having an enlarged projecting portion 67 affording oppositely disposed lateral areas 68 against which a blow may be struck at one side to close the door and at the same time force the bar into clamping position, or at the opposite side to release the bar and at the same time open the door.

The notch 58 is deep enough to allow for a certain amount of wear of the wedging surfaces 62 and 63, although shallow enough to prevent overtravel of the door relative to its seat during closing movement. Opening movement of door 23 and lever 53 is limited by a stop bar 69 in the form of an angle, with one leg 71 within a conforming recess 72 and clamped between flanges 36 and 37, and the other leg 73 upstanding and positioned for engagement by door arm 46, the leg 73 forming a stop for the door in an open position substantially as indicated by the broken outlien in Fig. 3. The stop bar 69 thus maintains the weight of the lever and door sufficiently off dead center to hold the door open, and furthermore above the common pivotal axis 51 so that a single blow against an area 68 of lever 53 is sufficient to return the door to the closed and securely clamped position. Moreover, in the open position as determined by stop bar 69, a portion of door 23 overlaps a portion of door seat 41 to enable the door to be readily returned to the closed position. In this open position also, there is no interference with corresponding movable parts on an adjacent similar closure unit, as indicated toward the left in Fig. 3, thereby permitting close spacing of adjacent units and the provision of ports of at least 2 in. diam. at each of the intertube spaces between tubes arranged at spacings as close as 6 in. center-to-center. In order that the weight of the lever and door may be maintained at a suitable distance off dead center when open and at the same time prevent interference with a closely adjacent unit, it is desirable to locate the pivotal axis 51 about as shown, at an angle "A" of about 5° below the line of symmetry of the door frame member 21, the displacement from the vertical thus being about 40°.

Figs. 6, 7 and 8 illustrate a modified form of lance door assembly similar in construction and operation to the embodiment already described although somewhat more compact and lighter in weight for a given size of lance opening. Parts of similar construction and function are accordingly designated by corresponding reference numerals supplemented in each case by the letter-suffix "a." In the modified form, the outer frame member or base plate 21a is provided with a circular bolting flange 36a with holes 39a for cap screws 28 circumferentially spaced and on horizontal and vertical axes as previously. In this form, the bolt 47a which forms the common pivot support for the door 23a and operating lever 53a is screwed into the base plate lug 48a, thereby obviating the need of locking nuts formerly required. An additional distinction is that the base plate 21a includes an integral stop member in the form of a radially extending rib 75 for limiting the opening movement of door 23a. It will be further noted that the arm 46a on door 23a includes a lateral extension 76 which carries an integral projection or stop pin 78 which when brought into engagement with the stop rib 75 determines the limit of door opening movement, the position of pin 78 relative to the stop rib 75

in the open position of door 23a being indicated by the broken outline in Fig. 6.

The modified form of operating lever 53a is formed with an oblong projection 79 extending transversely of its length and positioned directly over the centrally positioned recess 54a and cover boss 56a. Diagonally opposite portions 81 of projection 79 are cut away at an angle as shown to provide clearance with respect to a closely adjacent closure unit to permit the lever 53a and door 23a to be swung into their fully open positions. The projection 79 provides flat striking areas 82 at opposite ends against which a blow may be struck at one end for moving the door 23a into its closed, seated position, and at the opposite end for releasing the door from its seated position and at the same time moving it into its fully open position.

While in accordance with the provisions of the statutes we have illustrated and described herein the best forms of our invention now known to us those skilled in the art will understand that changes may be made in the form of the apparatus disclosed without departing from the spirit of the invention covered by our claims, and that certain features of our invention may sometimes be used to advantage without a corresponding use of other features.

We claim:

1. A closure unit comprising a frame formed with an opening therein and providing a door seat peripherally of said opening in a plane transverse to the axial extent of said opening, a door for said opening slidably movable with respect to said seat, said door including a body portion of symmetrical formation about a central axis and arranged to engage said seat throughout the perimeter of said opening in the closed position of said door, a door operating bar for moving said door, means at one side of said door seat pivoting said bar for movement of said door parallel to the plane of said seat, said door having an arm pivoted on said pivoting means for movement in a plane also parallel to said door seat whereby said bar and said arm are pivoted about a common pivotal axis, means continuously coupling said bar to said door to effect door opening and closing movement directly in response to pivotal movement of said bar, means including said bar for continuously preventing displacement of said door longitudinally of said pivotal axis, and stationary means on said frame engageable by said bar in the closed position of said door for applying a force to said door clamping said body portion against said seat, said coupling means connecting the inner face of said bar to the outer face of said door and being centrally arranged with respect to said body portion for transmission of said clamping force along said central axis, said means coupling said bar to said door being formed as a pin-and-socket connection comprising a pin of circular cross-section projecting axially outwardly from the body portion of said door and received in a circular socket formed in said bar, said pin having an axial length greater than the depth of said socket and contacting only the base of said socket while maintaining all other portions of said door spaced from said bar.

2. A closure unit comprising a frame having a circular opening therein and providing an annu-

lar door seat peripherally of said opening in a plane transverse to the axial extent of said opening, a door for said opening slidably movable with respect to said seat, said door including a body portion of circular formation about a central axis and arranged to engage said seat throughout the perimeter of said opening in the closed position of said door, a door operating bar for moving said door, means at one side of said door seat pivoting said bar for movement of said door parallel to the plane of said seat, said door having an arm pivoted on said pivoting means for movement in a plane also parallel to said door seat whereby said bar and said arm are pivoted about a common pivotal axis, means continuously coupling said bar to said door to effect door opening and closing movement directly in response to pivotal movement of said bar, means including said bar for continuously preventing displacement of said door longitudinally of said pivotal axis, stationary catch means on said frame formed with a wedging inner surface engageable by said bar in the closed position of said door for applying a force to said door clamping said body portion against said seat, said coupling means connecting the inner face of said bar to the outer face of said door and being centrally arranged with respect to said body portion for transmission of said clamping force along said central axis, and stop means associated with said frame and cooperating with said arm at a location intermediate the length of said arm for limiting door opening movement to a position wherein said door is clear of said opening while overlapping a portion of said seat.

3. A closure unit as defined in claim 2 wherein said stop means is formed as a member secured in fixed relation to said frame and having a portion extending from the plane of said seat into the path of movement of said arm.

4. A closure unit as defined in claim 2 wherein said stop means is formed on said frame as a rib extending radially between said pivoting means and said frame opening, said door arm including a projection extending toward said frame and adapted to contact said rib upon movement of said door into said specified open position.
